UNITED STATES PATENT OFFICE.

HERVEY N. ANDREWS, OF GREENFIELD, INDIANA.

ADJUSTABLE BED.

No. 806,091.

Specification of Letters Patent.

Patented Dec. 5, 1905.

Application filed April 20, 1905. Serial No. 256,671.

To all whom it may concern:

Be it known that I, HERVEY N. ANDREWS, a citizen of the United States, residing at Greenfield, in the county of Hancock and State of Indiana, have invented certain new and useful Improvements in Adjustable Beds, of which the following is a specification.

This invention relates to improvements in adjustable beds, and has special reference to the adjustment of the bed-bottoms or mattress-holding portions, whereby parts adjacent to the head of the bed may be elevated into position oblique to the major lower portion of the bed-bottom, as is often desirable with invalids when it is desired to permit them to assume a sitting or partially-sitting posture.

I accomplish the objects of the invention by the mechanism illustrated in the accompanying drawings, in which—

Figure 1 is a longitudinal vertical section of my improved bed, showing the bottom in its horizontal position; and Fig. 2 is a like longitudinal vertical section showing the bottom adjusted to an oblique position for the portion thereof adjacent to the head of the bed.

Like characters of reference indicate like parts throughout both views.

While I have here shown a wooden bedstead, it is obvious that my invention is equally applicable to iron and other metal beds, and I therefore do not desire to limit my invention to the particular kind of bedsteads shown in the drawings.

Referring to the drawings, 1 represents the head, 2 the foot, and 3 the side rail connecting said head and foot. Secured to the inner side of the side rail adjacent to the foot 2 is the block 4, having an upper oblique edge which slopes downwardly from the top of the rail 3. This edge has a longitudinal groove to receive a tongue 5 on the end of the board 6. This tongue is shown in dotted lines in the drawings. The board 6 extends approximately two-thirds of the length of the side rail 3, and its end having the tongue 5 is oblique to fit the oblique end of the block 4. Secured by means of the hinge 7 to the lower corner of the opposite end of the board 6 is the bar 8, which is pivotally secured at 9 to the side rail 3. The end of the bar 8 adjacent to the board 6 is made tapering, as shown, so as not to interfere with the lowering of the board 6 by the contact of the bar with

said board when the latter is moved in a downward direction. This downward movement of the board 6 would be attended by a swinging upward movement of the outer end of the bar 8. The movement of the bar 8 below the horizontal line of the bottom of board 6 is prevented by the block 10, which is fastened to the lower edge of the side rail 3 for the purpose of forming a stop to arrest said bar 8.

Connected by means of the hinge 11 to the upper inner corner of the board 6 is the bar 12. The bar 12 has a bearing upon the roller 13, and the roller 13 is mounted upon the adjacent edge of the bar 8.

By the above construction it will be observed that a lowering of the board 6 will cause the bar 8 to swing in an upward direction, and thereupon the bar 12 will be forced by the bar 8 into a corresponding oblique upward position, such as is clearly illustrated in Fig. 2. Any desired angular position of the oblique parts with relation to the board 6 may be obtained within the range of adjustment of the bed, and in order to maintain a given adjustment I provide the longitudinally-slotted bar 14, which is pivotally connected at one of its ends to the ears 15, fastened to the under side of the bar 8. A bolt 16, supported by the side rail 3, is located between the ears 15 and 85 hinge 7 (speaking now of the horizontal position of the bed-bottom) and this bolt passes through the longitudinal slot in the bar 14 and terminates with a screw-threaded end, on which a wing-nut is screwed, as shown in the drawings. By screwing the nut in against the slotted bar the latter can be locked, and thereby a given position of the adjustable bar 8 will be held. The ears 15 and bolt 16 when placed as above described and as shown in the drawings will cause the bar 14 to fold up automatically against the under side of bar 8 when the bed-bottom is in its horizontal adjustment.

I have here described the construction and operation of parts as applied to one of the bed-rails, and as the parts are merely duplicated for the other bed-rail it is obvious that the description given for one side, as above, will suffice for both.

Any suitable mattress will be attached to the board 6 and bar 12. In the drawings I have shown a wire mattress 18, but do not desire to be limited to that kind of a mattress.

Having thus fully described my invention,

what I claim as new, and wish to secure by Letters Patent of the United States, is—

1. In a bed, the bed-rails, blocks secured to the inner side of said bed-rails at the foot, 5 said blocks having upper edges which slope downwardly toward the head of the bed, horizontal vertically-movable boards each having oblique ends resting upon the oblique edge of its respective block, bars for each bed-rail 10 pivoted to its rail and hinged at its end to the lower corner of its adjacent board, a second bar hinged to the upper corner of each board and bearing upon the underlying pivoted bar.
2. In a bed, the bed-rails, blocks secured to 15 the inner side of said bed-rails at the foot, said blocks having upper edges which slope downwardly toward the head of the bed, horizontal vertically-movable boards each having oblique ends resting upon the oblique edge of 20 its respective block, bars for each bed-rail pivoted to its rail and hinged at its end to the lower corner of its adjacent board, a second bar hinged to the upper corner of each board and bearing upon the underlying pivoted bar, 25 and means to hold a given adjustment of the above parts.
3. In a bed, the bed-rails, a bar pivoted to each bed-rail, a board hinged to the end of said bar having vertical adjustments against

a bed-rail, means to support and guide the 30 opposite end of the board, a second bar for each rail hinged to the end of said board and bearing upon the pivoted bar, a longitudinally-slotted bar pivotally secured at one end to the pivoted bar, a bolt passing through the 35 slotted bar, and a nut on said bolt.

4. In a bed, the bed-rails, a bar pivoted to each bed-rail, a roller on each of said bars, a board hinged to the end of said bar and having vertical adjustment against a bed-rail, means 40 to support and guide the opposite end of the board, a second bar for each rail hinged to the end of said board and bearing upon the roller on the pivoted bar, a longitudinally-slotted bar pivotally secured at one end to 45 the pivoted bar, a bolt passing through the slotted bar, and a nut on said bolt said bolt being located between the pivotal connection of the slotted bar and the hinge between the pivoted bar and board.

50
In witness whereof I have hereunto set my hand and seal, at Indianapolis, Indiana, this 15th day of April, A. D. 1905.

HERVEY N. ANDREWS. [L. s.]
